Primary Examiner — Michael A Pratt

(57) **CLAIM**

The ornamental design for a valve, as shown and described.

DESCRIPTION

1.-3. Valve

1.1 : Perspective

1.2 : Front

1.3 : Back

1.4 : Top

1.5 : Bottom

1.6 : Right

1.7 : Left

2.1 : Perspective

2.2 : Front

2.3 : Back

2.4 : Top

2.5 : Bottom

2.6 : Right

2.7 : Left

3.1 : Perspective

3.2 : Front

3.3 : Back

3.4 : Top

3.5 : Bottom

3.6 : Right

3.7 : Left

Designs 1-3: valve; the thin lines in the drawings illustrate the shapes of the surfaces; the broken lines in the drawings illustrate environmental structures that form no part of the claimed designs.
